PENNSYLVANIA, A CORPORATION OF PENNSYLVANIA

PNEUMATIC SUCTION BOX FOR SUCTION ROLLS

Application filed November 16, 1928. Serial No. 319,824.

This invention relates to a suction roll for a paper machine, or other machines employing suction in any form, and is more particularly concerned with means for assuring contact between the suction box and the revolving shell of the roll. Such a machine is of utility in any of the textile, felt or allied industries wherein moisture is to be removed by suction.

10 An object of the invention is to provide a suction box having resiliently mounted packing strips.

Another object is to provide a suction box which will conform to any irregularity in the contour of the suction roll, throughout its length.

Another object is to dispense with mechanism in the interior of the suction chamber.

Another object is to provide a suction box from which the packing strips can be withdrawn from the end of the roll for renewal without dismantling the roll and removing the suction chamber.

Another object is to provide a suction roll 25 in which the adjustable deckles can be removed from either end without dismantling the roll, the deckle packing strips having the same resiliency and adjustment as the longitudinal packing strips.

30 Another object is to provide a fluid-controlled, adjustable suction box.

Still another object is to produce a suction box with adjustable packing strips the adjustment of which is controlled by air.

35 A further object is to provide means in a suction roll whereby access may be readily had to the interior.

A still further object is to produce a suction roll characterized by the simplicity of its construction.

Yet another object is to produce a new and improved suction roll.

Other objects will appear hereinafter.

In the drawings which illustrate one form of my invention,

Fig. 1 is a longitudinal section through the left hand portion of a suction roll according to the invention;

50 Fig. 2 is a longitudinal section similar to

Fig. 1 of the right hand portion of the suction roll;

Fig. 3 is a view on an enlarged scale taken along the line 3—3 of Fig. 1;

Fig. 4 is an end view of the structure 55 shown in Fig. 1;

Fig. 5 is a section taken along the line 5—5 of Fig. 1;

Fig. 6 is a section on the line 6—6 of Fig. 3;

Fig. 7 is a section on an enlarged scale taken along the line 7—7 of Fig. 1 and illustrating details, while

Fig. 8 is a plan view of the coupling shown in Fig. 6.

The suction roll comprises a perforated shell 1 closed at each end by a head 2. As well understood, the shell 1 may be supported in any suitable manner as by bearings 3 and 4, the heads 2 preferably carrying integrally formed journals 5. The journals of course, may be attached to the heads 2 in any desired manner. Also carried by the bearings 3 and 4 are the hollow trunnions 6 and 7, each of which at their inner ends act as closures for the suction box 8. The trunnion 6 extends through the journal 5, and is connected at its outer end to a suitably adjustable conduit or suction elbow 9 by means of which suction is applied through the suction box 8 to the rotating shell 1.

As shown in Fig. 5, the suction box 8 comprises a rounded portion 10 having a plurality of upstanding arms 11, each terminating in a head 12 which carries the packing strips 13 in a manner to be hereinafter described. Loosely mounted on the floor of the head 12 is a tube-support 15 for carrying the pneumatic tube 16. This tube, when inflated, operates to lift the flexible holders 14 for the packing 13 and functions to completely seal the suction box at all times. As will be readily understood, any wear will be assimilated entirely in the packing strips, which because of their resilient mounting will always be urged snugly against the interior of the rotating shell 1.

At each end of the suction box there is preferably mounted an adjustable deckle 100

support 17 which, while it may be of any convenient construction, preferably takes the form shown in Fig. 7. Carried on the supports 17 are deckles 18 which are reciprocated through longitudinal paths by members 19 which are guided by shafts 21 and 22. The members 19 are provided in the present instance with a recess 19a terminating at its inner end in a small opening 19b which extends through to a cavity or recess 19c extending around the shafts 21 and 22. The shafts 18a on which the deckles 18 are carried terminate at their inner ends in a head 18b having a downwardly extending lug 18c fitting snugly in the recess 19a. By means of the play permitted in the recess 19a, the shaft 18a is free to move up and down without danger of binding as would be the case if the head 18b were fixed to the member 19. The opening 19b is provided to act as a vent between the cavity 19c and the recess 19a, thus preventing back pressure from building up in the recess 19a. The member 19 shown in Fig. 1 is actuated by a shaft 20, in the form of a sleeve fitting about a shaft 20a which actuates the rear member 19. As well understood, the position of the deckles determines the length of the suction box, and consequently the width of the paper produced. The shaft 20a may be carried by hangers 23 and is preferably provided at its left hand end with a hand-wheel 24, while the shaft 20 is actuated by a crank 25 by means of which they can be turned, either together or separately, to cause the threaded portions 26 and 27 to actuate the members 19.

The crank 25 is preferably provided with extensions or arms 25a by means of which the longitudinal displacement of the rear deckle may be readily determined from a scale back of the arms.

The deckles 18 each carry a transverse packing strip 28 which cooperates to seal the ends of the suction box. Underneath the deckles are carried packing plates 29, which close the openings 30 and 31 in the deckle support 17, as well as the space between the support and the rib 32, which at each end of the roll joins the arms 11 along the portions thereof which define the travel of the deckles. While the plates 29 may be of any desirable material, they are preferably formed of vulcanized rubber, fibre, or a phenol condensation product. The plates are shown as being secured by suitable means such as screws 33 to the deckle support 17.

It will be noted from an inspection of Fig. 7 that the packing holders 14, are provided on their adjacent faces with lugs 34 which engage with corresponding recesses in the deckle support 17. It will be readily seen that in this manner the deckle support 17 will be carried up and down along with

the packing holders 14, insuring engagement of the packing strips 28 with the shell 1.

The tubes 16 which extend substantially the full length of the suction box are actuated by any suitable means such as piping 35 on which may be mounted if desired, an air intake valve 36, pressure regulator 37, and pressure gauge 38. The compressed air travels through pipe 39, to elbow 40, and thence upwardly to the union 41, where the flow is split into two parallel paths. Each stream then passes through a section of rubber tubing or the like to a nipple 43. The tubing is provided to give the necessary flexibility to the air conduit. The nipple 43 is preferably connected to the tube 16 by suitable means such as a jamb nut 44 which extends through packing holder 14, and lock nuts 45 and 46. At its outer end, the nipple is threaded into a nut 47 which is provided with a swinging yoke 48 carrying a set-screw 49. A dimple 50 is provided in the face of the nipple 43 for cooperation with the set-screw.

By this construction, it is possible to readily remove a defective nipple by merely backing off the set-screw 49 and swinging the yoke to such a position that the nipple 43 can be removed. The use of the valves 36 and 37, and gauge 38 lends a further advantage in that adjustment of the packing strips is effected by compressed air, controlled by the regulating valve 37, the pressure of which is indicated by the gauge 38; the compressed air chamber under the packing affording uniform adjustment and resiliency to the packing in contact with the inner surface of the revolving shell.

As shown in Figs. 1, 2 and 4, the heads 2 are provided with diametrically opposed openings 51 and 52, by means of which access may be had to the interior of the suction roll. Inasmuch as there are no parts of the mechanism on the interior of the roll, it can be washed down by suitable means, such as by hose passed through openings 51 or 52, to remove any clay and lime, or similar deposits on the interior of the shell. Prior to such cleaning, the deckles 18 are removed through the openings and the packing strips displaced longitudinally therethrough to disengage them with the packing holders 14, thus providing ready access to the interior of the shell. It will be seen that the packing strips 13 when worn, may be quickly removed and replaced by new ones.

One of the pedestals 53 on which are carried the bearings 4 is preferably provided with an arm 54, pivotally mounted at 55 and adapted to hold the journals 6 of the suction box 8 stationary while the shell 1 is rotating. The angle of the suction box to the vertical may be varied by means of the threaded arm 56 which is pivotally con-

nected at 55 to arm 54 and which is provided with stops 57 for limiting the travel of the arm 54.

With this pneumatic adjustable suction box, the tension of the seal packing against the inner surface of the revolving shell is in no wise affected by the varying vacuum within the suction chamber. If in a long roll under high vacuum, the main vacuum chamber should be raised or sprung, it cannot affect the tension of the rubber packings against the shell, as this deflection will be taken care of by the resiliency of the pneumatic tubes.

15 Only a slight tension is required between the packing and the revolving shell, and this tension can be regulated through the air regulating valve and will be at all times indicated on the pressure gauge at the air intake.

20 This last feature is a very distinct advantage, as in all of the mechanically operated adjustable suction boxes, there is no means of determining the amount of tension which 25 is being exerted on the packing. If the vacuum on the roll falls, no matter from what cause, the tendency is to tighten up the packing which increases the power required to drive the roll and unnecessarily 30 wears out the packing. In other words the stationary suction chamber may deflect due to its length or it may rise or spring upwards, due to excessively high vacuum, without in any way affecting the tension of the 35 packing strips against the revolving shell.

As a result of the structure according to the above description, it is possible to keep the packing strips 13 and 28 uniformly 40 pressed against the suction roll 1 throughout the entire length of the suction box. It is further possible to remove the strips 13 without dismantling the suction roll, the strips being merely moved longitudinally 45 of the supports 14. A still further advantageous feature has been pointed out, that the interior of the roll can be washed down through the openings 51 and 52. Yet another advantage is that the deckle and the 50 longitudinal packing strips can be pressed as a unit against the interior wall of the shell 1.

It is of course understood that the invention is susceptible to numerous modifications and adaptations, and it is intended that it 55 be limited only by the scope of the appended claims.

We claim:

1. In a suction roll having a deckle and a suction box, packing strips for said deckle and said suction box, and means for resiliently pressing said packing strips against the interior of said roll with a pressure uniform throughout the length of the strips.

60 2. In a suction roll, a suction box, flexible packing strips on said suction box, flexible

bars in which the strips are mounted and means engaging the bars for resiliently pressing said packing strips against the interior wall of said suction roll to seal the suction box and to compensate for irregularities in the bore of the roll.

3. In a suction roll, a suction box in the interior of said roll, flexible packing strips on said suction box adapted to engage the interior walls of said roll and to seal said suction box, flexible bars by which said strips are carried and means engaging the bars for yieldingly pressing said strips against said wall with a pressure uniform throughout the length of the strips to compensate for irregularities in the bore thereof.

4. In a suction roll, a suction box with longitudinally adjustable deckles mounted thereon carried in said roll, packing strips on said suction box and said deckles, flexible 65 bars upon which said packing strips are carried, means engaging the bars for lifting said deckles and said packing strips to resiliently press the packing strips against the interior wall of said roll, and means for sealing the ends of said suction box when the deckles are lifted clear thereof.

5. In a suction roll, a suction box carried therein, longitudinally adjustable deckles loosely mounted on said suction box, packing 85 strips carried by said deckles and said suction box, flexible bars upon which said packing strips are carried, means engaging the packing strips for lifting said deckles and said packing strips to resiliently engage the 100 packing strips with the interior wall of the roll, and sealing plates for sealing the ends of the suction box when the deckles are lifted clear thereof.

6. In a suction roll having a rotatable outer shell having heads and a stationary suction box, means for compensating for wear between said shell and said suction box comprising packing strips loosely mounted in longitudinally extending upstanding arms of said suction box, said packing strips being removable through the ends of the arms and means connected with each of said arms for resiliently pressing said packing strips against the interior wall of said shell, at 110 least one of said heads having openings permitting access to and removal of said strips.

7. In a suction roll having a rotatable outer shell and a stationary suction box, spaced upstanding arms mounted on said suction box and extending longitudinally of said roll, packing strips carried in said arms, longitudinally adjustable deckles carried between said arms adjacent the ends thereof and operatively supported by said packing strips, packing strips carried on said deckles, and means for resiliently lifting the first-mentioned packing strips and thereby said deckles so that all the packing strips yieldingly engage the inner walls of said shell.

8. In a suction roll having a rotatable outer shell and a stationary suction box, upstanding arms on said box and extending longitudinally of said shell, packing strips loosely mounted in said arms; longitudinally adjustable deckles carried between said arms adjacent the ends thereof and operatively supported by said packing strips, packing strips on said deckles, means for lifting said first mentioned strips and thereby said deckles so that all of the deckles clear said arms and the packing strips are yieldingly pressed against the interior wall of said shell, and means for sealing the ends of said suction box when the deckles are lifted clear thereof. 70
9. In a suction roll, an outer shell and a stationary suction box having spaced upstanding arms extending longitudinally of said shell, means interconnecting said arms adjacent the ends thereof, air tubes carried by said arms, said tubes being seated on loosely mounted supports, vertically adjustable packing strips seated in adjustable holders mounted above said air tubes, and deckle supports carried by the said means and vertically adjustable along with said packing strips, the air tubes being adapted to yieldingly press said packing strips against the interior wall of said shell and to lift deckles mounted on said supports so that the packing strips carried by said deckles will also be yieldingly pressed against the said shell. 80
10. In a suction roll having a rotatable outer shell and a stationary suction box, spaced arms extending upwardly from said suction box, and means interconnecting said arms adjacent their ends, longitudinally extending tubes mounted on said means adjacent its extremities, longitudinally extending packing strips mounted above said tubes for vertical adjustment, shouldered holders for carrying said packing strips, deckle supports mounted on said means and engaging said shoulders, deckles carried by said supports and having packing strips mounted thereon, said air tubes being operable to lift said deckle supports, and both the longitudinally-extending and the deckle packing strips to yieldingly engage them with the inner wall of said shell. 90
11. In a suction roll having a rotatable outer shell and a stationary suction box, spaced arms extending upwardly from said suction box substantially the full length of said shell, air tubes mounted in said arms, vertically adjustable packing strips carried above said air tubes, and shouldered means fitting over said air tubes for carrying said packing strips, deckle supports extending between said shouldered means adjacent the ends of said suction box, said shouldered means having longitudinally extending keys for engaging corresponding grooves in said deckle supports, and deckles carried by said supports and having packing strips thereon extending transversely of said arms, said air tubes being operable to lift said packing strips to yieldingly engage the interior wall of said shell. 100
12. In a suction roll having a rotatable outer shell and a stationary suction box, upstanding arms on said suction box and extending longitudinally of said shell, air tubes carried in said arms, shouldered means mounted on each of said tubes and being vertically adjustable, said means each carrying a longitudinally extending packing strip, vertically adjustable deckle supports carried between said shouldered means adjacent the ends of said arms, and deckles carried by said supports, and having packing strips thereon extending transversely of said suction box, said air tubes being adapted to lift said shouldered means and said deckle supports to yieldingly engage the packing strips with the interior wall of said shell. 110
13. In a suction roll having a rotatable outer shell and a stationary suction box, upstanding arms mounted on said suction box and extending longitudinally thereof, air tubes carried by said arms for yieldingly engaging packing strips with the interior wall of said shell, and means comprising a swinging yoke for demountably engaging said air tube with an air line. 120
14. In a suction roll, a suction box in said roll having upstanding arms extending longitudinally thereof, said arms terminating in longitudinally slotted heads, packing strips mounted in said slotted heads and being movable longitudinally thereof, and heads closing the ends of said roll, one of said last mentioned heads being provided with an opening whereby access may be had to the interior of said roll for removing said packing strips therethrough. 130
15. In a suction roll, a suction box having an upstanding arm thereon terminating in a longitudinally extending slotted head, a packing strip mounted in said slotted head and being movable longitudinally thereof, and heads closing the ends of said roll, said heads each being provided with an opening whereby access may be had to the interior of said roll for removing said packing strips therethrough. 140
16. In a suction roll, a suction box having packing strips mounted thereon and adapted for longitudinal movement along said suction box, deckles on said suction box, and heads closing the ends of said roll, each head being provided with an opening whereby access may be had to the interior of said roll for removing the adjacent deckle and the packing strips therethrough. 150
17. In a suction roll, a suction box within the roll having longitudinally-extending 160

arms, flexible packing means mounted in said arms and means urging the flexible packing means against the inner wall of the roll with a pressure uniform throughout the length of the packing means.

5 18. In a suction roll, an outer shell, an interiorly-disposed suction box having longitudinally-extending arms, flexible packing means mounted on each arm and movable

10 toward the inner wall of the shell and fluid pressure means acting directly upon said flexible packing means to urge it toward the wall of the shell.

15 19. In a suction roll, an outer shell, an interiorly-disposed suction box having longitudinally-extending arms, flexible packing means mounted on each arm and movable toward the inner wall of the shell and fluid pressure means acting directly upon said flexible packing means to urge it toward the wall of the shell, said packing means affording an area unbalanced to the suction created within the box whereby the packing means is urged outwardly by said suction.
